UNITED STATES PATENT OFFICE.

MARION M. MCCOY, OF DAWSON, NEW MEXICO, ASSIGNOR OF ONE-HALF TO G. A. WILL,
OF ST. LOUIS, MISSOURI.

SPARK-PLUG.

1,395,923.

Specification of Letters Patent.

Patented Nov. 1, 1921.

Application filed December 7, 1916. Serial No. 135,604.

To all whom it may concern:

Be it known that I, MARION M. McCoy, a citizen of the United States, residing at Dawson, county of Colfax, State of New Mexico, have invented a certain new and useful Improvement in Spark-Plugs, of which the following is a full, clear, and exact description, such as will enable others skilled in the art to which it appertains to make and use the same, reference being had to the accompanying drawings, forming part of this specification.

My invention relates to spark plugs for internal combustion engines, the principal object of my invention being to provide a spark plug with an attachment which performs the functions of a blow-out valve and a priming device, said attachment being very simple in structure, effective in use and adapted to be combined with practically all the various types of spark plugs now in general use.

A further object of my invention is to provide means for simultaneously opening and closing the entire series of combined blow-out valves and priming devices applied to an engine, thereby making it possible for the driver of the motor vehicle, from his position on the vehicle seat to effect the blowing out of carbon and the like from the engine cylinders while said engine is in operation.

With the foregoing and other objects in view, my invention consists in certain novel features of construction and arrangement of parts, hereinafter more fully described and claimed and illustrated in the accompanying drawings, in which—

Figure 1 is a plan view of an internal combustion engine, the cylinders thereof being fitted with spark plugs of my improved construction.

Fig. 2 is a plan view of one of my improved spark plugs.

Fig. 3 is a vertical section taken approximately on the line 3—3 of Fig. 2.

Referring by numerals to the accompanying drawings, which illustrate a practical embodiment of my invention, 10 designates the body of the spark plug, the same being provided at its lower end with an extension 11 which is externally threaded in order that said extension may be screw seated in the wall of an internal combustion engine.

The body 10 and extension 11 are provided

with a common chamber 12, the lower end of which terminates in a restricted opening 13 in the bottom of extension 11. Seated in the bottom of the extension 11 and projecting into the restricted opening 13 is an electrode or spark point 14.

Screw seated in the upper end of the body 10 is a plug 15 the same carrying a substantially cylindrical member 16 of insulation and carried by said member is an electrode 65 or spark point 17, the lower end of which terminates adjacent to the end of member 14.

Chamber 12 is comparatively large and as the lower portion of member 16 extends only a short distance downward into the upper portion of said chamber, the latter is comparatively free or open and devoid of narrow pockets or recesses, which latter, it will be understood, tend to collect carbon and the like. The tendency of carbon and the like to enter this comparatively large open chamber is materially reduced by the restricted opening into the lower portion of said chamber, and which opening is partially closed by the ends of the electrodes 75 14 and 17.

Screw seated in the wall of the body 10 is one end of a tubular member 18, the same performing the functions of a valve housing and the outer end of this member is extended 85 upward and terminates in a cup-shaped member 19. Formed through the horizontal portion of this member 18 is a diametrically arranged tapered aperture 20 and mounted for rotation therein is a tapered plug 21, 90 the same being provided with an aperture 22 which is adapted to coincide with the passageway through said member 18. Under normal conditions, this plug is turned so that the aperture 22 is at right angles or out 95 of register with the passageway through the member 18 and when said plug is turned so that said aperture registers with the passageway, carbon and like accumulation within the engine cylinder will find exit upwardly 100 through chamber 12 and thence outwardly through the passageway in member 18, or in the event that it is desired to prime the cylinder, the priming fluid may be poured into cup-shaped member 19, and 105 said fluid will pass from thence through the spark plug into the cylinder.

In order to effect the simultaneous opening and closing of all of the spark plugs utilized on a multi-cylinder engine, I have 110

arranged an apparatus comprising a rod 23 from which projects a series of short arms 24, and the ends of the latter are pivotally connected to the outer ends of fingers 25, the same being fixed to the projecting ends of the plugs 21.

One end of the rod 23 is connected to a retractile spring 26, the same normally holding said rod 23 in position with all of the 10 valves closed. The opposite end of rod 23 is pivotally connected to one end of a lever 27, preferably in the form of a bell crank, and the opposite end of said lever being connected in any suitable manner to a pedal 15 or lever which is located convenient to the seat occupied by the driver of the vehicle.

In the event that it is desired to effect the discharge of carbon or other accumulation within the cylinders of the engine to which 20 plugs are applied, the lever or pedal is actuated to operate lever 27, thereby shifting rod 23 lengthwise, and through the connections 24 and 25 all of the plugs are partially rotated so as to bring the apertures 25 26 into register with the passageway through the members 18, and while the engine is running, the carbon or other accumulations within the cylinders will be blown outwardly through the spark plugs and through 30 the passageways through the members 18. The electrodes form the spark gap in the restricted mouth of the chamber 12 and in the blowing out operation, above described, any carbon which might accumulate on the 35 electrodes or in the chamber 12 will be in the path of the air and burnt gases expelled from the cylinder through the restricted mouth of chamber 12 (at the bottom thereof) and through the opening in tube 18 (at 40 the top of chamber 12) and thus the electrodes and chamber 12 will be cleaned.

As soon as the pull upon the lever 27 is released, spring 26 will act to return rod 23 and parts connected thereto to their normal 45 positions, thereby simultaneously closing all of the valves connected to the spark plugs.

Spark plug attachments of my improved construction are comparatively simple, can be readily combined with practically all 50 forms of spark plugs now in general use, and provide effective means for permitting the accumulations within the cylinders of an engine to be blown out while the engine

is in operation, and likewise provide simple means whereby the cylinders may be easily 55 and quickly primed.

It will be readily understood that minor changes in the size, form and construction of the various parts of my improved spark plug attachment can be made and substituted 60 for those herein shown and described, without departing from the spirit of my invention, the scope of which is set forth in the appended claim.

I claim:

The combination with a multi-cylinder internal combustion engine, of a series of spark plugs seated in the cylinder block of the engine with one spark plug projecting into each cylinder of the engine, each of 70 which spark plugs comprises a body that is provided with a comparatively large chamber having a restricted opening at its lower end, an electrode fixed to the body of the spark plug and projecting into said 75 restricted opening, a second electrode extending through the body of the spark plug and insulated therefrom, the lower end of which second electrode terminates within the restricted opening adjacent to the end 80 of the first mentioned electrode, and there being a threaded aperture formed through the side wall of the plug, which aperture communicates with the chamber, of a tubular member one end of which is threaded 85 and screw seated in the aperture in the plug, the outer end of said tubular member being turned upwardly and formed into a cup which is open to atmosphere, a valve mounted for rotation within said tubular 90 member and passing diametrically therethrough, said valve being provided with an aperture which is adapted to register with the passageway through the tubular member, an operating handle carried by each 95 valve, a pull rod pivotally connected to the outer ends of all of said handles, and a retractile spring for moving said pull rod in one direction.

In testimony whereof I hereunto affix my 100 signature in the presence of two witnesses, this 4th day of December, 1916.

MARION M. McCOY.

Witnesses:

M. P. SMITH,
M. A. HANDEL.
